UNITED STATES PATENT OFFICE.

HENRY HAMMOND, OF HARTFORD, CONNECTICUT.

IMPROVEMENT IN PORTABLE LUBRICATORS.

Specification forming part of Letters Patent No. **99,082**, dated January 25, 1870.

To all whom it may concern:

Be it known that I, HENRY HAMMOND, of Hartford, in the county of Hartford and State of Connecticut, have invented a new and Improved Oil-Cup; and I do hereby declare that the following is a full, clear, and exact description of the same, reference being had to the accompanying drawings, and to the letters of reference marked thereon.

Figures 1 and 2 are top views of two different forms of the improved oil-cup. Figs. 3 and 4 are vertical sections of the same through the middle of the cup.

Like letters in the several figures indicate like parts.

My invention consists in furnishing the oil-cup with a conical valve, A, which is operated by a screw, E, and regulated and controlled by an index, G, attached to the head, so that any desired quantity of oil may be allowed to pass through the aperture B to the machinery. The valve A is at the lower end of the stem C, which works through the cover or top D of the oil-cup, with a screw, E.

Attached to the head F of the screw is an index, G, which serves to show the amount the valve A is opened. It also serves as a clamp-screw to hold the head F firmly in any desired position when set. The point of this index can be set at any point of the graduated arc 0 1 2 3, &c., Figs. 1 and 3, which numbers are intended to show the number of drops passed in a given time through the valve A.

H is the cap of the feeding-hole, which is

removed to fill the oil-cup. In Figs. 1 and 2 this aperture is shown in the top of the cup. In Figs. 3 and 4 a different arrangement is shown. The feeding-tube *a a* passes through the stem C, and the cap H is placed upon the top of the head of the screw F. The cap H is furnished with an air-hole, *b*, which admits the air to supply the place of the oil expended.

I is a screen, for the purpose of separating any impurities that may be in the oil and preventing their reaching the valve A.

The operation of my invention is as follows: When the valve A is closed, in the position shown in the drawings, the index G is at zero of the scale 0 1 2 3, &c., and no oil will pass through the valve. If, now, the index be moved to 1, by turning the head of the screw E, the valve A will be slightly opened and one drop of oil passed through in ten minutes, or some other given time. At 2, 3, &c., two and three times the same quantity passes through the valve, and so with the other graduations. By this means I am enabled to regulate the flow to any desired quantity.

What I claim as my invention, and desire to secure by Letters Patent, is—

In combination with an oil-cup, the cap or top D, screw-valve stem E, feeding-orifice *a*, cap H, having an air-hole, *b*, and set or index screw G, working through the head F.

HENRY HAMMOND.
